UNITED STATES PATENT OFFICE.

THOMAS F. LAWSON AND WILLIAM K. BURTON, OF ATHENS, GEORGIA.

BASKET.

SPECIFICATION forming part of Letters Patent No. 354,713, dated December 21, 1886.

Application filed July 1, 1886. Serial No. 206,851. (No model.)

To all whom it may concern:

Be it known that we, THOMAS F. LAWSON and WILLIAM K. BURTON, citizens of the United States, residing at Athens, in the county of Clarke and State of Georgia, have invented certain new and useful Improvements in Baskets; and we do hereby declare the following to be a full, clear, and exact description of the invention, such as will enable others skilled in the art to which it appertains to make and use the same.

Our invention relates particularly to baskets of the class in which a folding frame of rigid material is combined with and supports a bag or body of cloth or other flexible material.

The invention is fully explained in this specification, and shown in the accompanying drawings, in which—

Figure 1 is a perspective view of the folding frame of our improved basket. Fig. 2 is an end elevation of the complete basket. Fig. 3 is a transverse vertical section of the top bar of one of the frame-sections and the margin of the bag attached thereto. Fig. 4 is an enlarged view, partly in section and partly in end elevation, showing a means of fastening the cover over the mouth or top of the basket; and Fig. 5 is a detail view showing one end of the hem E' of the flap E and the rod F projecting therefrom.

The frame of the basket illustrated in these figures consists of two rigid rectangles, A A' A'' and B B' B'', each of the rectangles being composed of two side bars and two cross-bars, and the two rectangles being connected by pivots C C, passing through the side bars, preferably at their centers. The side bars of the two rectangles are halved at their ends to receive the cross-bars, for the purpose of avoiding any projecting or irregular surfaces at the angles of the frame, and this feature of construction is desirable, though not essential.

The body of the basket is a bag of any suitable fabric, and having preferably a rectangular bottom. It is supported by the upper cross-bars, A' B', of the frame, and may be fastened to them in any desired manner, but preferably in the way shown in the drawings—that is, by forming a wide hem, D', about the mouth of the bag, inserting the bars A' B' in the hem, and fastening the bars to the respect-

ive side bars, A A' B B', by means of screws or nails passing through the cross-bars and the material which incloses them. This means has the advantages of cheapness, simplicity, and security. It really adds nothing to the cost of either the frame or the bag, (since the hem is necessary to properly strengthen the margin of the bag,) and the bars, when inserted in the hem, give the bag a more perfect and uniform support than could be afforded if the edge of the bag were fastened to the bars by tacks or nails placed at intervals.

A flap or cover, E, is fastened to the bag just below one of the bars, as A', Figs. 3, 4, one edge of the cover being stitched to the bag and the other edge being free. This cover may be stretched across the mouth of the bag and fastened in place in various ways; but we prefer the means illustrated in the drawings, which consists in inserting a rod, F, in a hem, E', at the free edge of the flap or cover, and, further, in providing the side bars, B B', with hooks G, adapted to receive the ends of the rod F, the rod being somewhat longer than the edge of the flap to which it is attached. While other practical fastenings can easily be devised, the one illustrated is simple and inexpensive, and has the merit of applying a uniform strain to the cover. It is evident that while the primary office of the flap E is to cover the bag, the parts may, in large baskets, be made heavy enough for the frame and cover to constitute a substantial and durable camp-stool; and for this use we believe the fastening F G to be especially desirable. The edge of the flap may be fastened to the cross-bar A' instead of to the bag, though we prefer to have the bag and cover detachable from the frame, as shown, and the securing-rod F may be caught in slots or notches G cut in the bars B, if desired. To avoid weakening the frame, however, it is preferable to use separate hooks G, as first suggested.

The basket described and illustrated is simple in construction and admirably adapted for shipment. The frames may be made by any mechanic, and may be packed, either with or without the bags, with the utmost economy of space. The bags, if made of proper material, are exceedingly durable, and when worn out they can be replaced quickly and at slight cost.

What we claim as our invention, and desire to secure by Letters Patent, is—

1. The combination, in a basket, of a supporting-frame, a bag having a hem about its margin, and bars inserted in said hem and fastened to said frame.

2. The combination of the pivoted side bars, A A B B, the cross-bars A' A'' B' B'', connecting the side bars, and the bag D, having the 10 hem D', said bars A' B' being inserted in said hem and rigidly fastened to the side bars, substantially as shown and described, and for the purpose set forth.

3. The combination, with the frame and the 15 bag D, suspended therein, of the flap E, having

one of its edges fastened at one side of the frame and bag, the rod F, attached to the free edge of the flap, and hooks G, or their equivalent, attached to the frame and adapted to receive and retain the rod E, and secure the free edge of the flap when stretched across the bag, substantially as and for the purpose set forth. 20

In testimony whereof we affix our signatures in presence of two witnesses.

THOMAS F. LAWSON.
WILLIAM K. BURTON.
